UNITED STATES PATENT OFFICE.

JAMES T. MILLEN, OF THOMASVILLE, GEORGIA.

PLOW.

SPECIFICATION forming part of Letters Patent No. 292,243, dated January 22, 1884.

Application filed December 12, 1883. (No model.)

To all whom it may concern:

Be it known that I, JAMES THOMPSON MILLEN, a citizen of the United States, residing at Thomasville, in the county of Thomas and State of Georgia, have invented new and useful Improvements in Plows, of which the following is a specification.

My invention relates, principally, to the class of shovel-plows; but the improvements which I have made are applicable to any plow which has a heel and standard connection for shovel-cultivator or mold-board.

The object of my improvements is to avoid the clogging of the brace which usually supports the shovel-holding standard, while at the same time bracing it thoroughly and preserving the old-fashioned connection of the handles with the beam. This object I carry out by the means hereinafter described, reference being had to the accompanying drawings, in which—

Figure 1 represents a view in perspective of a cultivator-shovel plow embracing my improvement, and Fig. 2 a rear view of the same.

The handles A A, which may be of wood, are preferably fastened to the beam B half-way between the clevis and standard-connections. The standard C is cast integral with the usual heel-piece, D, as shown. It has also a clip-socket, a, for the shovel, as is well understood. Bent wrought-iron braces E E extend from both plow-handles in such manner as to be connected to the beam B at its rear end by a bolt, b, and, downwardly extending, are also bolted to the heel D, which is provided with a projection, c, for the bolt b', for the reason that when the bolt-connection is far down in the heel-piece it will be rendered useless as the latter wears. The braces E E curve, as shown, to suit their connection with the beam and heel-piece, and are flattened at the termination of the curve to form eye-holes for the bolt-connection with the beam. I prefer to make these braces flat; but they may be made round. All the parts except the handles are preferably of wrought-iron, as that material is not only

strong, but is of lighter weight; but they may be cast, all except the braces E E; which must be of wrought-iron.

In my plow I have produced not only a light structure, easily drawn by one horse; but I have avoided lateral movement of the beam and dispensed with the front clogging-brace, all in one plow.

Plow-handles have been braced to the beam in various ways by separate bent braces, and the plow has been braced to the beam by separate braces in various ways, and a single brace has been arranged to connect the heel of the plow-standard to the beam and to one of the handles. My improvement differs from such constructions in the particulars of the bent braces bolted to the opposite sides of the standard-heel, to the opposite sides of the beam, and to the handles, whereby both the latter are firmly braced to the heel of the plow-standard and the latter to the beam, giving a firm support for the standard-heel in the direction of the beam and laterally, and employing such heel-support as the means for bracing the handles in every direction.

I claim—

1. The combination of the plow-standard C, having the heel D, with the bent braces E E, the beam B, and the handles A, the said braces being bolted to the plow-heel, the beam, and to the handles, in the manner shown and described.

2. The combination, with the beam and the handles, of the plow-standard having its heel D terminating in an upward extension, c, and the bent braces E E, bolted to the opposite sides of said heel-extension, the opposite sides of the beam, and to the handles, as shown and described.

In testimony whereof I have hereunto set my hand in the presence of two subscribing witnesses.

JAMES T. MILLEN.

Witnesses:

H. B. ZEVELY,
J. W. HAMILTON JOHNSON.
